SAFE GUARD

Henry Beach and William H. Schaller, Jenera,
Ohio

Application August 8, 1932, Serial No. 627,954

9 Claims. (Cl. 20—1.01)

This invention relates to a safe guard for bank windows, post office windows or the like, and has for an object to provide a safe guard preventing the possibility of the banker or post office clerk being held up by a robber on the other side of the window.

It is a further object of this invention to provide a safe guard which can be instantly placed into operation so as to prevent the possibility of bullets coming through the usual opening and striking the clerk.

A further object of this invention is to provide a safe guard which may be operated either by the clerk from a concealed trip near the floor out of sight of the would be robber, or by a person at a convenient distance from the window who is out of range of the would be robber.

Still a further object of this invention is to provide a safe guard which may be used at as many windows as desirable and may be operated simultaneously at all windows to form an impenetrable bullet shield between the clerks and the would be robber.

Still a further object of this invention is to provide a protected opening in the shield whereby the clerk may shoot through the shield after it has been operated without exposing himself to the sight of the would be robber.

With the foregoing and other objects in view, as will hereinafter become apparent, this invention comprises the constructions, combinations, and arrangements of parts, hereinafter set forth, claimed, and disclosed on the accompanying drawings. In these drawings,

Figure 1 is an elevation view of a bank window with the safe guard in open position.

Figure 2 is a similar view with the safe guard in closed position.

Figure 3 is a rear view of Figure 1.

Figure 4 is a rear view of Figure 2.

Figure 5 is an enlarged view of the lower section of Figure 3 showing the operating mechanism.

Figure 6 is a top view of Figure 1.

Figure 7 is a top view of Figure 5.

Figure 8 is a vertical end view of the bank window with the shields open.

Figure 9 is a view similar to Figure 8 with the shields closed.

Figure 10 is a detail view showing the crank handle in operative position.

Figure 10' is a top view of the lower half of Figure 10.

Figure 11 is a view on the left side of Figure 10'.

Figure 12 is a section on line 12—12 of Figure 11.

Figure 13 is a top view of the window ledge showing the crank attaching clip holder in dotted outline.

Figure 13' is an edge view of Figure 13.

Figure 14 is a detail showing how the various ropes are attached.

Figure 15 is a section on line 15—15 of Figure 5.

Figure 16 is a sectional view of the safe guard release.

Figure 17 is a top view of Figure 16.

Figure 18 is a side view of the remote foot control for the safe guard.

Figure 19 is an elevation view of the gun hole 70 and cover.

Figure 20 is a section through Figure 19.

Figure 21 is a side view of the pulley fitting, and

Figure 22 is a perspective view of the operating mechanism.

There is shown at 25 the frame work of a bank window of a cashier's or bank clerk's cage, the frame 25 being preferably made of steel, or other bullet proof material, and should preferably extend from the floor to the ceiling. Extending down from the counter ledge 26 is a steel partition 27 and extending upwardly from the top of the grill 28 is another steel partition 29, the grill 28 having the usual raisable grill section 30 so that it may be opened to pass larger bundles 85 therethrough when necessary in the course of business, the open portion of the grill section being shown at 30 in dotted outline in Figure 1, and the raised portion of grill section 30 being received within the partition 29.

As will be apparent, the cashier will be completely protected by the steel frame work and partitions, except for the space between the counter 26 and top of grill 28, and this invention particularly supplies means for providing instantaneous protection for this otherwise exposed portion in time of emergency, which the cashier himself or some one else at a distance may operate without the operation being visible to the desperado outside the cashier's window. The exposed portion is adapted to be protected by two steel partitions 31 and 32 which when in position place an impregnable steel barrier between the cashier and such desperados as may be attempting to hold him up. One or both of these partitions will have a bullet opening 33 therethrough protected by a swinging steel shutter 34 pivoted thereto at 35 and operable by the knob 36 from the cashier's side only, thus enabling him to hold the would-be robbers at bay.

The lower partition 31 is connected to the upper partition 32 by a cable 37 operating over pulley 38 which is rotatably affixed to within the hollow framework 25, as shown in Figure 21. By 5 this connection, the dropping of the upper partition 32 will raise the lower partition 31, and vice versa, the dropping of the lower partition will raise the upper partition.

The partitions 31 and 32 being of substantially 10 equal size, will also be of substantially equal weight, and hence each partition will balance the other, thus causing both partitions to remain in any set position.

Extraneous means are provided for moving the 15 partitions together to the protecting positions and for separating them again to return the cashier's window to its normal open position. A weight 39 connected by a cable 40 and operating over pulley 41 is connected to the top of lower partition 31 20 as by the eye 42, there being a weight 39 on each side of the partition, thus balancing the opposite sides of the partitions, and causing them to operate smoothly. As will be seen in Figure 8 the partitions travel up and down in the tracks 43 25 formed in framework 25, and ledges 44 are affixed to the tops and bottoms of each partition. The weights 39 thus tend to raise the lower partition 31, thus permitting the upper partition 32 to fall at the same time, and meet in the position shown in Figures 2 and 4.

Means are provided for holding the partitions in separated position and for releasing them to allow them to come together to the protective position. A pawl 45, sharpened as at 46, bears 35 against the lower partition 31 as shown in Figure 16, and slides in an arm 47 affixed to framework 25, a tension spring 48 tending to keep the pawl 45 bearing against the ledge 44 of partition 31. A lever 49 is affixed to pawl 45 through pin 40 50, and the lever 49 is operated to withdraw pawl 45 against the tension of spring 48 by means of a rod 51 rotatably affixed to brackets 52.

A foot pedal 53 is connected by levers 54 to rotate rod 51 and thus trip pawl 45 and release the 45 partitions to the protective position. When the cashier is attacked, he has only to kick his foot against the pedal 53 to instantly release the partitions and protect himself, it being observed that his actions would be entirely concealed from the 50 would-be robber. Should the cashier be unable to kick the pedal, either as a result of his being too far therefrom to reach it without giving notice to the would-be robber, or as a result of the cashier being shot without notice, a remote control lever 55 on rod 51 is operated by connecting rod 56 from lever 57 of foot pedal 58. The remote foot pedal 58 may be placed at any convenient location in the bank, preferably outside the cashier's cage, whereby another person, as a bank guard, may 60 operate whenever the bank is being held up. The remote pedal 58 may be connected to operate any number of protective partitions at a number of different windows, thus making it possible to instantly protect every counter window in the bank 65 simultaneously.

After the emergency is over, it is necessary to separate the partitions and restore them to the position ready for immediate operation again whenever the emergency arises. A rod 60 is rotatably affixed between opposite portions of frame 70 25 as at 61 and bears a beveled gear 62 thereon. This rod 60 has a cable 63 detachably affixed thereto, as at 64 in Figure 15, the other end being temporarily affixed to partition 31 to pull it down 75 by any convenient means, as by an eye similar to

eye 42, and thus through cable 37, raise the upper partition 32.

A bracket 65 is permanently affixed to the underside of ledge 26, whereby to receive an arm 66 projecting from a sleeve 67 of a crank shaft 68 having a gear 69 adapted to be placed in mesh with gear 62 to operate the rod 60. A handle 70 serves to rotate the crank shaft 68, while a forked bracket 71 projecting from the lower end of sleeve 67 over rod 60 serves to hold the gears in mesh while the partitions are being separated. When the partitions are fully separated, the bevel of point 46 on pawl 45 permits the pawl to retract and then be pressed against the partition 31 to hold it ready for instant operation. The crank is then removed, and cable 63 likewise removed, so as to eliminate slowing up the operation of the partitions in an emergency. As will be apparent from the drawings, the operating details may be 80 85 90 95 100 105 110 115 120 125 130 135 140 145 150 155 160 165 170 175 180 185 190 195 200 205 210 215 220 225 230 235 240 245 - transaction of business, means for bullet proofing said opening, said means comprising an upper and a lower shield, means connecting said shields for simultaneous movement toward and from each other, and operative control means for said shields comprising means tending to move said shields toward each other to protective position, and trip means holding said shields apart, said trip means comprising a pawl in pressure engagement with one of said shields, a lever for withdrawing said pawl from engagement to release said shields, and a foot pedal for operating said lever. 5 and from each other and means for operating said shields away from each other to the non-protective position.
6. A safe guard for bank cage windows comprising a bullet proof frame, said frame having an opening therethrough permitting the regular transaction of business, means for bullet proofing said opening, said means comprising an upper and a lower shield, means connecting said shields for simultaneous movement toward and from each other, and operative control means for said shields comprising means tending to move said shields toward each other to protective position, and trip means holding said shields apart, said trip means comprising a pawl in pressure engagement with one of said shields, a lever for withdrawing said pawl from engagement to release said shields, a foot pedal for operating said lever, and a connecting rod between said lever and said foot pedal whereby said foot pedal may be located at a distance from said cage window. 10 8. A safe guard for bank cage windows comprising a bullet proof frame, said frame having an opening therethrough permitting the regular transaction of business, means for bullet proofing said opening, said means comprising an upper and a lower shield, means connecting said shields for simultaneous movement toward and from each other, and means for operating said shields away from each other to the non-protective position comprising a rotatable rod, a cable for temporarily connecting one of said shields to said rod, and crank means for rotating said rod. 15 9. A safe guard for bank cage windows comprising a bullet proof frame, said frame having an opening therethrough permitting the regular transaction of business, means for bullet proofing said opening, said means comprising an upper and a lower shield, means connecting said shields for simultaneous movement toward and from each other, and means for operating said shields away from each other to the non-protective position comprising a rotatable rod, a cable for temporarily connecting one of said shields to said rod, crank means for rotating said rod, said crank means comprising a gear fixed on said rod, a bracket fixed on a cage element, a crank 20 shaft, a gear on said shaft adapted to mesh with said rod gear, a crank sleeve about said shaft, an arm on one end of said sleeve receivable in said cage element bracket, and a bracket on the other end of said sleeve cooperating with said rod. 25 100 105
7. A safe guard for bank cage windows comprising a bullet proof frame, said frame having an opening therethrough permitting the regular transaction of business, means for bullet proofing said opening, said means comprising an upper and a lower shield, and means connecting said shields for simultaneous movement toward 30 35 40 45 50 55 60 65 70 75 80 85 90 95 100 105 110 115 120 125 130 135 140 145 150
